CONTAINER

Jack Raisin, Burlingame, Calif.

Application June 4, 1934, Serial No. 728,818

3 Claims. (Cl. 229—8)

My invention relates to an improved construction for boxes.

It is an object of my invention to provide a two-piece box which simulates a book in appearance.

5 Another object of my invention is to provide a box which simulates a book in appearance and can be made on the present day automatic box-making machines thereby eliminating the expense of hand work.

10 Another object of my invention is to provide a box simulating a book in appearance the sections of which are separable so that in packing there is no hinged lid to interfere as the box is passed along the packing table.

15 Another object of my invention is to provide a box simulating a book in which are employed novel features of construction.

Other objects and advantages of my invention will appear from the following description and 20 from the drawing.

In the accompanying drawing forming a part of this specification, and in which like numerals are employed to designate like parts through the same,

25 Fig. 1 is a view in perspective of the assembled box,

Fig. 2 is a cross-section view taken on the line 2—2 of Fig. 1, but with the top lifted above the bottom,

30 Fig. 3 is a view in perspective showing constructional features,

Fig. 4 is a partial cross-section view taken on the line 2—2 of Fig. 1,

Fig. 5 is a view in perspective of the assembled 35 box, and

Fig. 6 is a perspective detail of the corner construction of the top.

My invention as shown in Fig. 1 is comprised of the bottom section A and the top section B.

40 These two parts are separable as shown in the cross-section view of Figs. 2 and 4.

The bottom of the box is comprised of the bottom 4 and side members 5. Attached to and overlying the bottom 4 is a piece of cardboard or 45 other suitable material 6, applied over the bottom of the box with three of its edges 7, 8 and 9 extending beyond the sides 5. The fourth edge 10 extends beyond the side 5 only for a very short distance,—just far enough so as to align with the 50 curved back of the top at 18 when the top and bottom of the box are in telescoped relation (see Fig. 4).

Overlying the bottom sections 4 and 6 and the sides 5 is a covering 11 of paper or other suitable 55 material.

The top of the box comprises the sides 12 and top 13. Attached to the top 13 is a cardboard or heavy material covering 14, so positioned on the top 13 that three of its edges 14, 15 and 16 extend beyond the sides 12 a distance sufficient 5 for them to align with the extended edges 7, 8 and 9 of the corresponding bottom section 6.

The fourth edge 17, of this portion 14 is made long enough to be bent over the side 12 and down to a point 18 where 17 and 12 abut. This bending of 17 is facilitated by a plurality of score marks 19 (see Figs. 2 and 4).

A covering 20, which may be of paper and suitably embossed (see Fig. 5), has cut-out sections (see Fig. 3) so that it may be applied in 15 one piece over the cardboard framework of the box top. The short flaps 20a, 20b and 20c are formed to cover the three sides 12 and the long flap 20d is shaped to cover the scored cardboard top portion 17, and to pull it in against 20 the fourth side 12 at 18. In Fig. 6 the scored portion 17 is shown with the flaps 20d and 20e pasted in place, but before the edge of the flap has been pasted over the side 12 so as to bring the parts 17 and 12 into abutment at 18, to 25 form the rounded back of the box.

In the assembly of the top section of the box the top 14 has been positioned with scored edge 17 extending out as shown in Fig. 3. Next, the paper cover 12 is applied over the top 14 and as 30 the automatic machine folds the cover 20 around the box the scored edge 17 is carried into position where its extreme edge coincides with the side of the box at 18.

By using the extending edge 17 on the top section 14, it is possible to make this box on the present day automatic machines with certain variations to accommodate the folding operation to bring the scored edge 17 into alignment with the side 12 at 18. It is thus possible 40 to dispense with any hand labor in the assembly of the top box section. By a suitable design representing the back of a book, embossed on the cover 20 in that section which overlies the scored edge 17, the box is given the appearance 45 of a book without the necessity of pasting on a separate back strip.

It is to be understood that the forms of my invention, herewith shown and described, are to be taken as preferred examples of the same, and that various changes in the shape, size and arrangement of parts may be resorted to, without departing from the spirit of my invention, or the scope of the subjoined claims.

Having thus described my invention, I claim: 55

1. In a two-part box with the sides arranged to look like a book, the combination of a bottom section having vertical walls bent up from a flat piece of material, a second sheet of flat material covering all of said bottom section, the edges of said second bottom sheet extending beyond the plane of said vertical walls, an equal distance on three sides and a short distance on the fourth side, a top section adapted to telescope over said bottom section having vertical walls bent up from a flat piece of material, a second sheet of flat material covering all of said top section, the edges of said second top sheet extending beyond the plane of said vertical walls an equal distance on three sides to align with the similar extensions on the bottom section, and on the fourth side forming a flap rounded down to abut with the edge of the vertical wall whereby when said top and bottom sections are telescoped the fourth side of said box presents a smooth rounded appearance.
2. A box comprising upper and lower telescoping sections, the lower section having a bottom and side walls with its bottom extended beyond said walls, a greater distance on three of its edges than on the fourth; the upper section having a bottom and side walls with its bottom likewise extended beyond said walls, a distance on three of its edges to align with the similar lower section bottom extensions, the fourth extension on the upper section bottom having a plurality of score marks parallel with the adjacent side whereby said extension is formed over said side and its free edge made to abut with the free edge of said side to give a rounded shape thereto.
3. A top section for a telescoping box comprising a bottom and sides, a piece of cardboard applied over said bottom, extending beyond three of said sides to form a margin and extending beyond said fourth side a distance greater than the height of said side to form a flap, the latter having score marks parallel with said side, and a one-piece covering applied over said cardboard and said sides, whereby the flap is held in place over said fourth side with its free edge in abutment with the free edge of said side.

JACK RAISIN.
